[57] CLAIM

The ornamental design for a foldable hand tool, as shown and described.

DESCRIPTION

FIG. 1 is a top, side and end perspective view of a foldable hand tool showing my new design in an operative state; FIG. 2 is a plan view thereof in the operative state; FIG. 3 is an elevation view thereof from the same side as in FIG. 1 and in the operative state; FIG. 4 is an elevation view thereof from the side opposite that in FIG. 3 and in the operative state; FIG. 5 is a front elevation view thereof in the operative state; FIG. 6 is a rear elevation view thereof in the operative state; FIG. 7 is a bottom view thereof in the operative state; FIG. 8 is a top, side and end perspective view thereof in a storage state; FIG. 9 is a plan view thereof in the storage state; FIG. 10 is an elevation view thereof from the same side as in FIG. 1 and in the storage state; FIG. 11 is an elevation view from the same end as in FIG. 1 and in the storage state; and, FIG. 12 is an elevation view thereof from the end opposite to that in FIG. 11 and in the storage state.

The portions of the foldable hand tool shown in dotted lines are for illustrative purposes only and do not constitute a part of the claimed design.
